UNITED STATES PATENT OFFICE.

EDWARD KAYE, OF MONACA, PENNSYLVANIA, ASSIGNOR TO THE PHOENIX
GLASS COMPANY, OF PITTSBURG, PENNSYLVANIA.

DESIGN FOR A CHIMNEY.

SPECIFICATION forming part of Design No. 29,835, dated December 20, 1898.

Application filed November 25, 1898. Serial No. 697,463. Term of patent 7 years.

To all whom it may concern:

Be it known that I, EDWARD KAYE, a citizen of the United States, residing at Monaca, in the county of Beaver and State of Pennsylvania, have invented a certain new and useful Design for Chimneys for Gas-Burners; and I do hereby declare the following to be a full, clear, and exact description of the invention, such as will enable others skilled in the art to which it appertains to make and use the same.

This invention has relation to a new and original design for gas-chimneys particularly adapted for use on gas-burners known as "incandescent" gas-burners.

The accompanying drawing is a side elevation of a chimney embodying my design.

The chimney consists of a main or body por-

tion A, which is outwardly flared at the top ²⁰ a and bottom a'. The top a is shouldered at b and is surmounted by the diminished portion c, which terminates in the top d, of smaller dimension than the body A, and which, is cylindrical in its outline. The lower portion of the body A terminates in the cup-shaped base B.

Having thus described my design, what I claim is—

The design for a chimney or similar article herein described and shown.

In testimony whereof I affix my signature in presence of two witnesses.

EDWARD KAYE.
